E. T. ADAMS

INTERNAL COMBUSTION ENGINE

Filed March 15, 1923

Inventor:
Edward T. Adams,
By *McDonald*,
Attorney

UNITED STATES PATENT OFFICE.

EDWARD T. ADAMS, OF PHOENIX, ARIZONA, ASSIGNOR TO FAIRBANKS, MORSE & CO., OF CHICAGO, ILLINOIS, A CORPORATION OF ILLINOIS.

INTERNAL-COMBUSTION ENGINE.

Application filed March 15, 1923. Serial No. 625,185.

This invention relates to internal combustion engines and especially applies to engines adapted for burning heavy oil.

An object of this invention is to construct and dispose a preliminary chamber so as to provide a cleaner burning mixture, and to prevent residual deposits of carbon or the like.

Another object is to construct and dispose a preliminary chamber, and to deliver the fuel thereto, so as to provide in an improved manner, two regions or zones in the chamber, one being an upper region or zone of lesser fuel concentration, and the other a lower region of greater fuel concentration.

Further objects include an improved shape of the preliminary chamber; an improved arrangement for cooling the walls thereof; novel means for maintaining temperature differences between regions of different fuel concentration; novel features of construction to effect desirable relative volumes and locations of the preliminary chamber and engine clearance space, with regard for the pressure and amount of injected fuel; and an improved arrangement of passages between the preliminary chamber and the clearance space.

Further objects and advantages of this invention will appear from the drawings and the following description.

I have illustrated a preferred example of the invention, in which the preliminary chamber is of a frusto-conical shape, completely surrounded, substantially over its full length, by a water jacket, and is provided with a replaceable liner of heat resisting material. The advantages of the chamber construction will be hereinafter referred to.

During operation, a more complete burning or explosion in the upper region of the chamber, serves to deliver the remaining fuel charge from the lower region to the main clearance space, to be further burned during the working stroke of the piston.

A means for maintaining a higher temperature in the upper region, of less fuel concentration, is found in the conical shape of this region, which provides greater volume to be cooled, through walls of uniform thickness. Cooling of this region is further relatively retarded by recessing, separating

or otherwise insulating a portion of the outer wall of the preliminary chamber. 55

The example described shows the replaceable liner as provided with a plurality of relatively small passages between the preliminary chamber and the clearance space. The passages should be large enough to allow a minimum drop in compression pressure in the preliminary chamber, yet restricted enough to prevent the explosive burning within the chamber from reaching the clearance space. The provision of such passages results in better regulation of rate of burning in the clearance space, and aids in mixing the air and fuel charge. The passages further serve to distribute fuel mixture throughout the clearance space, and prevent localized burning of the piston. 65 70

The passages leading to the clearance space are prevented from choking with carbon or the like by the close association of this part of the structure with the water jacket. Cracking of the fuel is thus prevented at this point, and the same constricted portion of the water jacket serves to keep cool the lower, concentrated fuel region of the preliminary chamber. 75 80

Referring to the drawings, which illustrate diagrammatically and merely by way of example, suitable means for effecting the invention:—

Fig. 1 is a sectional view of the combustion end of an internal combustion cylinder of the Diesel type, having the invention embodied therewith. 85

In Fig. 1, the combustion end of cylinder 10 is shown with the power piston 11, at the end of the compression stroke, leaving the clearance space 12. A conical recess 13 is provided at the top of the cylinder body which extends to the clearance 12. This space 13 receives the conical cup 14, forming the preliminary chamber 15, closed at the top by the plate or body 16, preferably bolted to the cylinder body and carrying the spray nozzle 17 and the channel 18 from a suitable source of supply, not shown. The outer peripheral wall of cup 14 is recessed as at 19, providing a space between said cup wall and the adjacent cylinder body wall, for the purpose to be described. At the apex of chamber 15, which, in the present example, is at the lower end, are provided the channels 90 95 100 105

or passages 20 discharging from chamber 15 into the clearance space 12, and preferably so inclined as to deliver the charge from chamber 15, well distributed throughout the clearance 12. While I may use to good advantage only one passage 20, yet for the purpose of preventing burning of the piston it is preferable to use a number of such passages in order to distribute the burning fuel over a larger portion of the main combustion clearance. It is obvious that I may make the narrow neck member integral with conical cup 14, but if desired the neck containing the communicating means may be made as a separate piece. The volume of the preliminary chamber should be less than one-half the total clearance, usually twenty-five per cent or less. When symmetrical in form and having its length or depth not too greatly exceeding its diameter, the volume may be twenty to twenty-five per cent of the total volume.

In the preferred form, the theoretical proportion between the region of greater fuel concentration and the region of lesser concentration, in the preliminary chamber, is approximately fifty per cent. This is very theoretical and considers only the volumes within and without the cone of spray.

30 The conical formation of the preliminary chamber secures or facilitates;

1. Concentration of fuel at the small end.
2. Better cooling effect because the water jacket is brought closer to the contents in the apex of the chamber and the passages delivering therefrom, thus reducing danger of cracking the fuel, and clogging the passages with tar and carbon.

3. Ample space for the region of lesser concentration at the base of the cone (in the present example, at the top of the chamber).

The nature of the formation of the combustible mixture in the region of lesser concentration, may be better understood by a consideration of the facts effecting it.

The fuel mixture in the space without the cone of spray is formed in various ways:—

(a). By friction between the surface of the cone of spray and the dense air through which it passes; the individual particles of spray are light and easily deflected, we might say, scraped off.

(b) By particles of fuel rebounding after striking the walls of the chamber.

55 (c) By particles of fuel carried upwards out of the cone of spray by the stream of heated air forced into the chamber through the channels 20, by the upward movement of the piston, at the moment when the injection begins. At this moment, the piston is rising and compressing air from the main clearance space into the preliminary chamber.

(d) By the turbulence created by the initial ignition of the fuel, this sudden expan-

sion of the gases in a portion of the chamber is probably an important factor.

(e) By the vaporization of fuel by contact with the heated air and by heat of combustion as it begins.

(f) The shape of the preliminary chamber and consequent variations in the area of the surface of the cone of spray, which is exposed to the air.

With these elements acting and coacting in various and somewhat uncertain degrees, it is only possible to approximate the degree of concentration in these outer regions, or where "lesser concentration" begins and "greater concentration" ends.

What I claim is:—

1. In an internal combustion engine, a frusto-conical pre-combustion chamber comprising a liner and having walls of substantially uniform thickness, adapted to be closely surrounded by a cooling fluid, and a closure means for said chamber.

2. In an internal combustion engine, a frusto-conical pre-combustion chamber substantially surrounded by, and uniformly separated from a cooling fluid, and an injection means therein adapted to inject the greater portion of the fuel charge into the lower part of said chamber.

3. In an internal combustion engine, a pre-combustion chamber, a frusto-conical liner therefor, a water jacket surrounding the sides of said chamber and a means associated with said liner adapted to produce a variation in temperature between upper and lower portions of said pre-combustion chamber.

4. In an internal combustion engine, a pre-combustion chamber, a frusto-conical liner therefor, a water jacket surrounding the sides of said chamber and heat insulating means associated with said liner and adapted to produce a variation in temperature between upper and lower portions of said pre-combustion chamber and an injection nozzle adapted to direct substantially the major portion of the fuel charge toward a relatively cool portion of said pre-combustion chamber.

5. In an internal combustion engine, a main combustion clearance, a pre-combustion chamber and a substantially frusto-conical liner therefor forming a plurality of fuel distribution passages in the lower portion of said chamber connecting with said clearance, said lower portion being relatively closely surrounded by a cooling fluid, and an injection nozzle adapted to direct substantially the major portion of the fuel charge toward said passages.

6. In an oil engine a substantially co-axial pre-combustion chamber and combustion clearance; liquid cooling means for said chamber and said clearance, relatively closely surrounding the lower portion of

said chamber, means extending through a short neck between said chamber and said clearance adapted to distribute burning fuel over a substantial area of said clearance, and a replaceable liner for said pre-combustion chamber substantially the length thereof.

7. In an oil engine, a pre-combustion chamber and a main combustion clearance; liquid cooling means about said chamber and said clearance; said chamber comprising an element adapted to contact with said cooling means and a second element located within said first named element and extending substantially the length thereof; said elements being arranged to provide a recess therebetween whereby differential heat conduction is effected between different portions of said elements; and a nozzle adapted to inject fuel into a relatively cool portion of said chamber.

8. In an oil engine, a pre-combustion chamber and a main combustion clearance; liquid cooling means for said chamber and said clearance; said chamber comprising an

outer portion and a replaceable inner portion substantially coextensive therewith, means between said outer and inner portions whereby a substantially higher temperature is maintained in the upper than 30 in the lower part of said pre-combustion chamber.

9. In an oil engine, a pre-combustion chamber and a main combustion clearance; liquid cooling means for said chamber and 35 said clearance; said chamber comprising an outer portion and a replaceable inner portion substantially coextensive therewith, insulating means between said outer and inner portions whereby temperature differences 40 maintain between upper and lower parts of said pre-combustion chamber; a nozzle coaxial with said chamber adapted to inject fuel to a relatively cool portion thereof; one of the portions of said chamber comprising a means whereby fuel is distributed 45 uniformly over a substantial area of said main combustion clearance.

EDWARD T. ADAMS.
